UNITED STATES PATENT OFFICE.

HARLAN W. OBENAUER, OF DETROIT, MICHIGAN.

CHECK-HOLDER FOR TOOL-ROOMS.

1,305,739.

Specification of Letters Patent. Patented June 3, 1919.

Application filed April 25, 1918. Serial No. 230,627.

To all whom it may concern:

Be it known that I, HARLAN W. OBENAUER, a citizen of the United States, residing at Detroit, in the county of Wayne and State 5 of Michigan, have invented a new and useful Check-Holder for Tool-Rooms, of which the following is a specification.

This invention relates to check holders for tool rooms.

10 Its object is to provide a check holder having a plurality of receptacles each adapted to hold a definite number of checks, said receptacles being of such a construction as to greatly facilitate the placing of checks 15 therein or their removal therefrom.

Another object is to provide a check holder that will arrange a large number of check holding receptacles compactly within a comparatively small space and which will 20 have the receptacles arranged in units, of which any desired number may be combined, so that the device may be readily adapted for the needs of either a large or a small shop tool room.

25 In attaining these objects the invention contemplates mounting a series of receptacle-forming bars in a spaced stepped relation upon suitably inclined standards, and associating with each bar a sign strip indicating the nature of the tools for which the 30 checks in the receptacles of said bar were received, the receptacles each being open at the front to expose the checks to view and having also an opening in the bottom to 35 facilitate grasping the checks for removal and replacement.

In the accompanying drawings,

Figure 1 is a front view of the device showing checks in certain of the receptacles.

40 Fig. 2 is an end view of the same.

Fig. 3 is a top view of one of the units wherein a series of check receptacles are formed.

Fig. 4 is a sectional view of said unit, the 45 section being taken on line 4—4 of Fig. 3.

Referring now more in detail to the drawing, wherein like reference characters are applied to similar parts in the several views, 1 designates a pair of triangular standards 50 which are positioned one at each end of the check holder. The bars 1^a of said standard are formed preferably of angle iron inclined at substantially forty-five degrees, and maintain a spaced stepped relation between a 55 series of check-holding bars 2, preferably formed of cast metal, said bars having in-

tegral lugs 3 at their ends which are seated upon the bars 1^a and secured thereto by bolts 4. It is desirable to have the bars 2 readily adjustable longitudinally of the bars 1^a so that the space intervals between said bars 2 may be increased or diminished according to the number of said bars used, and this result is secured by forming the bars 1^a with longitudinal slots 5 through which 60 the bolts 4 are passed.

Each of the bars 2 has formed therein a series of circular check receptacles 6 each having a segmental opening 7 in the front portion of its bottom to facilitate grasping 70 checks as they are being placed in or removed from the receptacles. The receptacles are open at the front and top thereof, their walls being curved forwardly beyond their common center line only a sufficient distance to insure against lateral displacement 75 of the checks forwardly.

The forwardly projecting lower portions of the receptacle walls 8 are offset to form shoulders which determine by their height 80 the intended capacity of the receptacles, which conveniently may be ten checks, since this number may be easily grasped between the thumb and forefinger. The rear portions of the receptacle walls have a somewhat greater height than the portions 8, so as to assist in guiding and quickly registering the checks with the receptacles before 85 they are lowered into the same.

Above each bar 2 there is disposed a sign 90 strip 9 indicating the nature of the tools in exchange for which the checks in the receptacles of said bar were given, the names of each tool being placed close adjacent to the receptacle or receptacles intended to receive checks exchanged for said tool, the spaces between the bars being sufficient to accommodate and display said signs. These signs are preferably formed of sheet metal and are held in place by clamping their end 100 portions between upwardly projecting integral portions of the lugs 3 and the bars 1^a. At the left-hand end of the check holder the sign-forming strips project as indicated at 10, forming tabs for an alphabetical index, 105 so that it may be known at a glance which of the several signs lists any given tool. Thus for example, if a check for a drill is to be removed from the holder, the attendant will by reference to the tabs 10 note which of the 110 signs 9 must include drills in its list of tools. Then having located the word "drill" on

said sign it is known that the check sought will be in one of the receptacles 6 just below said word.

The above described check holder is 5 equally well adapted for either a large or a small shop, since the standards 1 may carry only a single bar 2 or a considerable number of such bars may be mounted upon said standards. Upon loosening the nuts of the 10 bolts 4, the slots 5 will allow a quick readjustment of the bars upon the standards when it is desired to increase or decrease the number thereof.

What I claim is:

15 1. In a check holder, the combination with a pair of supporting standards, each having an inclined longitudinally slotted bar, of a series of bars mounted in spaced stepped relation upon the inclined bars of said stand-

ards each formed with a series of check 20 holding receptacles and with terminal lugs engaging said inclined bars, and members for adjustably clamping said adjustable bars to the standards, passing through the lugs of the bars and the slots of the standards. 25

2. In a check holder, the combination with a pair of supporting standards each having an inclined top face, of a series of bars mounted in spaced stepped relation upon the inclined faces of said standards each formed 30 with a series of check holding receptacles and with terminal lugs engaging said inclined bars, and securing means for said bars engaging said lugs and the standards.

In testimony whereof I sign this specifica- 35 tion.

HARLAN W. OBENAUER.
